UNITED STATES PATENT OFFICE.

THOMAS GRISWOLD, JR., OF MIDLAND, MICHIGAN, ASSIGNOR TO THE DOW CHEMICAL COMPANY, OF MIDLAND, MICHIGAN, A CORPORATION OF MICHIGAN.

APPARATUS FOR CHEMICAL REACTION ON HEATED SOLID MATERIAL.

Application filed January 27, 1927. Serial No. 163,930.

This invention relates to apparatus for chemical reactions where there is a mass of solid material and a gasiform substance, at elevated temperature; and it is among the objects of the invention to provide for efficient vaporizing and supplying such substance, also for removing refuse from the site of reaction. Other objects and advantages will appear as the description proceeds.

To the accomplishment of the foregoing and related ends, the invention, then, consists of the features hereinafter fully described, and particularly pointed out in the claims, the following description and the annexed drawings illustrating but one of the various ways in which the principle of the invention may be employed.

In said annexed drawings:—

Fig. 1 is a vertical sectional view of an embodiment of the invention; Fig. 2 is a vertical section taken on a plane at right angles to that of Fig. 1; Fig. 3 is a sectional detail on larger scale; and Fig. 4 is a view at right angles to Fig. 3, with the door removed and the setting partly broken away.

The reference character 1 in the drawing designates a reaction chamber or retort 1, preferably separable or removable and of tubular form, round or elliptical or of other desired cross section. Beneath each retort, a clean-out chamber combined with a vaporizer is arranged. This may take the form of a receptacle 2 having a horizontal partition 3 therein, the compartment above the partition serving as an ash or refuse receiver, while the compartment below the partition serves as a vaporizing chamber. The supply conduit or pipe 4 opens into or connects with the lower compartment, and may have a trap 5, the main supply of the material to be vaporized being furnished from a valve-controlled pipe 6. The receptacle 2 has a door or closure 7, and the partition 3 is spaced back therefrom substantially to allow free communication from the lower compartment to the upper and to the retort. A pedestal 8 may be provided, preferably integrally, for the support of the receptacle 2.

Surmounting the retorts are heads 9, which may be of sufficient capacity to provide magazine feed, and each head has a closure 10 and an outlet connection 11 lead-

ing to a condenser or absorber system, (not shown).

In the same general setting, a gas producer or generator 12 is included, masonry walls in common being preferably employed, and from the producer a duct 13 communicates directly with mixing ports 14 in conjunction with an air supply flue 15. The air supply flue is arranged in a regenerator or recuperator construction with the outgoing flue 16 for the stack gases, and in this manner the air feed for the combustion system is brought up to temperature facilitating efficient combustion. From the ports 14, a flue system surrounds the retorts and the receptacles 2, vertical and horizontal baffles being arranged to divert the hot combustion products for circulation about the respective units.

In operation, the retorts 1 are charged through the magazines 9 with the solid material to be employed. In the case of carbon disulphide manufacture, this will be carbon, in the form of charcoal for instance. The temperature is brought up by combustion in the flue system to a red heat for instance in the case of CS₂ manufacture, and the material to be vaporized is supplied from the pipe 6 into the vaporizing compartment at the base of receptacle 2. In the case of sulphur, it is preferable to melt the sulphur in a suitable melter, not shown, and forward the molten sulphur through the pipe, regulating the feed as required by the valve. The products of reaction in gaseous form are taken off through the outlet 11 to the condenser or absorber system.

The retorts 1 may be made of ceramic material or of metal, as cast iron, to suit the process being worked. Similarly the receptacles 2 may be made of ceramic material or of metal, and a one-piece or integral construction is particularly desirable. For carbon disulphide manufacture, a ceramic retort and cast iron-vaporizer is preferred.

With the assembled units in compact arrangement together with the heating means, as in accordance with this invention, heat introduced into the system is utilized to its largest extent and a uniformity of control is to be had in a manner not obtainable in isolated and separate unit construction. Moreover, the arrangement of the vaporizer is such as to utilize heat effectively and

at the same time not interfere with the functioning of the clean-out portion.

Gas mixing ports may be provided to add combustible to the flames at any point desired, as for instance beyond the retort and before the vaporizer if additional heat in excess of that available from the spent gas be required there. In this way the larger portion of the heat may be supplied to the vaporizers if desired.

Other modes of applying the principle of the invention may be employed, change being made as regards the details disclosed, provided the means stated in any of the following claims, or the equivalent of such, be employed.

I therefore particularly point out and distinctly claim as my invention:

1. In apparatus of the character described, the combination of a reaction chamber, and separate chambers for an ash pot and a vaporizer thereunder.

2. In apparatus of the character described, the combination of a reaction chamber, separate chambers for an ash pot and a vaporizer thereunder, and heating flues about the reaction chamber, the ash pot and the vaporizer.

3. In apparatus of the character described, the combination of a reaction chamber, and a one-piece partition-separated ash pot and vaporizer.

4. In apparatus of the character described, the combination of a reaction chamber, an ash-chamber thereunder, and a vaporizing-chamber under the ash-chamber.

5. In apparatus of the character described, the combination of a reaction chamber, a communicating receptacle thereunder having

a front closure, and a horizontal partition in said receptacle extending to a point spaced from the closure.

6. In apparatus of the character described, the combination of a reaction chamber, a communicating receptacle thereunder having a horizontal partition, and a heating flue surrounding said receptacle.

7. In apparatus of the character described, the combination of a reaction chamber, a communicating receptacle thereunder having a horizontal partition, and a feed conduit for supplying below the partition material to be vaporized.

8. In apparatus of the character described, the combination of a reaction chamber, a communicating receptacle thereunder having a front closure and a horizontal partition extending to a point spaced from the closure, and a heating flue surrounding said receptacle.

9. In apparatus of the character described, the combination of a reaction chamber, a communicating receptacle thereunder having a front closure and a horizontal partition extending to a point spaced from the closure, and a pedestal supporting said receptacle.

10. In apparatus of the character described, the combination of a reaction chamber, a communicating receptacle thereunder having a front closure and a horizontal partition extending to a point spaced from the closure, a feed conduit for supplying below the partition material to be vaporized, and a pedestal supporting said receptacle.

Signed by me this 14 day of January, 1927.

THOMAS GRISWOLD, JR.
